UNITED STATES PATENT OFFICE.

JACOB P. TIRRILL, OF ST. LOUIS, MISSOURI.

PAPER CONTAINER FOR WOOL.

1,160,961.

Specification of Letters Patent. Patented Nov. 16, 1915.

Application filed March 30, 1915. Serial No. 18,015.

To all whom it may concern:

Be it known that I, JACOB P. TIRRILL, a citizen of the United States, residing at St. Louis, in the county of St. Louis and State 5 of Missouri, have invented new and useful Improvements in Paper Containers for Wool, of which the following is a specification.

This invention relates to bags and sacks for wool and pertains especially to a paper 10 container made of a woven paper fabric for packaging and baling wool.

Heretofore wool bags have always been made of burlap, the fibers of which loosen and mix with the wool. These fibers will 15 not take the dyes and cause endless trouble in textile fabric manufacturing. For years it has been a great problem how to handle wool without contamination from burlap, hemp and twine. It has been known that 20 paper when used as a container has no deleterious effects on the wool, but the problem has been heretofore to make a container entirely of paper which is sufficiently strong to resist the tremendous pressure of wool 25 baling where a container is subject to a rending strain of five hundred pounds or more, per square inch. I have discovered a means for solving the problem which consists in weaving a paper container, of tough 30 paper threads to stand the wear and tear of such handling as wool bags are subjected to.

The drawing illustrates such a woven paper container.

In carrying out the invention, paper of a degree of toughness to provide necessary 35 strength and pliability is employed, the paper being woven into a relatively wide or large mesh fabric, preferably into bag-like form without seams. These bags are of suitable size to fit wool baling presses in use, 40 and when filled, the bags are sewed or closed at the end in any suitable manner. Experience shows that these woven paper bags not only possess the requisite degree of 45 strength and afford the desired protection to the wool, but they have the additional quality of in no wise contaminating the wool.

Having thus described my invention what I claim and desire to secure by Letters Patent is—

A package of wool composed of a container formed of tough woven paper relatively large mesh fabric capable alone of 55 withstanding baling pressure and in which the inner face of the fabric directly contacts with the wool.

In testimony whereof I have hereunto set my hand.

JACOB P. TIRRILL.
